UNITED STATES PATENT OFFICE.

FRANK J. CREQUE, OF CUYAHOGA FALLS, OHIO, ASSIGNOR OF ONE-HALF TO F. W. DODGE,
OF ASHLAND, OHIO.

BALLOON-INFLATOR.

No. 874,166.

Specification of Letters Patent.

Patented Dec. 17, 1907.

Application filed June 21, 1907. Serial No. 380,146.

To all whom it may concern:

Be it known that I, FRANK J. CREQUE, a citizen of the United States, residing at Cuyahoga Falls, county of Summit, and State of Ohio, have invented certain new and useful Improvements in Balloon-Inflators, of which the following is a specification, reference being had therein to the accompanying drawing.

- 10 This invention relates to a balloon inflator, and particularly to a structure of mouth piece adapted to support the balloon while being inflated and from which it may be released.
15 The invention has for an object to provide a novel and improved construction of balloon and inflating tube having an air chamber over which the balloon is adapted to be retained and from which it may be released by
20 a sliding latch when properly inflated.

A further object of the invention is to provide an improved construction of breathing valve in the air chamber, and also a noise producing device to be actuated by escaping air
25 from said chamber.

Other and further objects and advantages of the invention will be hereinafter set forth and the novel features thereof defined by the appended claims.

30 In the drawing:—Figure 1 is an elevation showing a balloon supported in position to be inflated; Fig. 2 is an enlarged longitudinal section of the inflator; Fig. 3 is a top plan thereof; Fig. 4 is an end view, Fig. 5 is a detail perspective of the nozzle, and Fig. 6 is a plan of the blank from which the tail is formed.

Like numerals refer to like parts in the several views of the drawing.

40 The numeral 1 designates a balloon which may be of any desired character or size, and if desired may be provided with a depending cord 2 carrying a steady or balancing weight 3 to guide the flight of the balloon
45 which may be of slitted paper as shown in Fig. 6 wound around a tapered cork center 3^a to form a conical tapered tail. This balloon is connected to a tubular nozzle 4 by attachment to the upper grooved portion 5 thereof, while the lower end of this nozzle is formed with a slotted shoulder 6 and tapered as at 7. The construction of the foregoing parts may be of any desired character, those herein shown and described being preferable to form a connecting device.

The inflator consists of the tubular mouth piece 8 provided at its outer end with an enlarged air chamber 9 which has secured to its upper face a yielding seat 10 provided with a central aperture to receive and form 60 an air tight connection with the tapering end 7 of the nozzle 4. This nozzle is held in contact with the valve seat by means of the sliding latch 11 provided at one end with a bifurcated or forked portion 12 to embrace the 65 tube 4 of the nozzle and at its opposite end with the operating handle 13. This latch is mounted upon the upper surface of the inflator 8 by means of the pins 14 extending through the slot 15 of the latch by which it 70 is guided in its longitudinal movement.

The air chamber 9 is provided with the breathing valve 16 which comprises a strip or flap of material being preferably of rubber and lying in contact with the curved 75 wall of the chamber with one end secured thereto at 17, while the opposite end extends over the opening through the mouth piece. By this construction the inward pressure of air through the inflator forces the valve 80 away from the seat, while if the operator desires to take a successive breath the valve is thrown tightly into its closed position. The pressure of air from the balloon also holds this valve closed under normal conditions. The air chamber is also provided at its lower portion with an outlet 18 therefrom which may have attached thereto any desired form of sound producing device, such, for instance, as a strip or elastic band 85 19 secured across the opening so as to produce a noise by the escape of air from the chamber and around the band. When such a band is used it may be readily secured in position by attachment at the grooved portion 20 of the inflator. Under some conditions it is desirable not to use this noise producing device and for that purpose the check 21 is pivotally mounted at 22 upon the inflator and provided with the curved head 100 23 which when swung into the position shown in full lines in Figs. 1 and 2 bears against the noise producing device and closes the outlet 18 from the air chamber. When it is not desired to use this device it 105 may be swung to one side as shown by dotted lines in Fig. 2.

In the operation of the invention, it is particularly adapted for the inflation of toy balloons in which the escaping air acts down- 110

- wardly to force the balloon upward thus producing a rocket balloon. This balloon is normally held by the latch until the desired pressure of air is accumulated therein 5 when it may be easily released and rises from its contact with the seat of the air chamber and continues to travel until the escaping air is reduced in pressure so that it gradually falls. It will be observed that the inflating tube is provided with a breathing valve to enable the operator to take a breath freely without applying the tongue to the end of the tube, and this valve is normally closed by the pressure in the air chamber 10 15 thus preventing the escape from the balloon through that tube. The bottom of the air chamber is provided with a noise producing device which may be used at will by simply swinging the check into or out of contact therewith, while this device may also be operated by the air from the balloon by simply retaining the latter in contact with the air chamber and swinging the check out of contact with the noise device. 20 25 The construction of the nozzle provides means for effecting air tight contact with the inflator and also the ready release of the balloon therefrom. This nozzle is also provided with means for the removable attachment of the cord connection from the tail thereto so that the balloon may be used with or without the tail as found most desirable. The tail is important in securing a rocket like flight of the balloon in a direct 30 35 path as the escaping air coming into contact with the tapering paper tail exerts a steady- ing influence upon the balloon and provides the necessary weight or ballast at the start of its flight. This pressure of air from the balloon decreases gradually in the flight thereof which consequently diminishes the steady- ing pull on the balloon in its downward travel.
- Having described my invention and set forth its merits, what I claim and desire to secure by Letters Patent is:—
1. In a device of the class described, an inflating tube provided with an air chamber at one end, and a latch member carried by the tube for retaining a balloon connection in communication with said chamber. 40 45
  2. In a device of the class described, an inflating tube provided with an air chamber at one end, a latch member carried by the tube for retaining a balloon connection in communication with said chamber, and an apertured elastic seat to receive said connection. 50 55
  3. In a device of the class described, an inflating tube provided with an air chamber at one end, a latch member carried by the tube for retaining a balloon connection in communication with said chamber, an apertured elastic seat to receive said connection, and a flap valve disposed upon the wall of 60 65
- said chamber and extending across a communicating passage through the tube. 70
4. In a device of the class described, an inflating tube provided with an air chamber at one end having a seat to receive a balloon connection, and shiftable means carried by the tube to retain said connection in contact with said seat. 75
  5. In a device of the class described, an inflating tube provided with an air chamber at one end, an apertured flexible seat secured to the upper face of said chamber, and a sliding latch provided with a bifurcated end disposed above said seat. 80
  6. In a device of the class described, an inflating tube provided with an air chamber at one end, an apertured flexible seat secured to the upper face of said chamber, and a sliding latch provided with a bifurcated end disposed above said seat and a slotted body mounted upon said seat. 85
  7. In a device of the class described, an inflating tube provided with an air chamber at one end, a flat valve secured to and traversing a portion of the vertical walls of said chamber to cover the passage leading thereto, and means for connecting a device to be inflated therefrom. 90
  8. In a device of the class described, an inflating tube provided with a discharge at one end, a sounding device secured to said discharge, and a pivotally mounted check carried by the tube to engage said sounding device. 95
  9. In a device of the class described, an inflating tube provided with a discharge at one end, a sounding device secured to said discharge, and a pivotally mounted check having a convex free end adapted to swing into contact with said sounding device. 100 105
  10. In a device of the class described, an inflating tube provided with an air chamber at its outer end, a seat at the upper portion of said chamber, a valve carried by said chamber to close the tube leading thereto, a sounding device disposed at the discharge opening from said chamber, and a check to engage said sounding device. 110 115
  11. In a device of the class described, an inflating tube provided with an air chamber at its outer end, a seat at the upper portion of said chamber, a valve carried by said chamber to close the tube leading thereto, a sounding device disposed at the discharge opening from said chamber, and a swinging check mounted upon the tube to engage said device. 120 125
  12. In a device of the class described, an inflating tube provided with an air chamber at its outer end, a seat at the upper portion of said chamber, a valve carried by said chamber to close the tube leading thereto; a sounding device disposed at the discharge opening from said chamber, a swinging check mounted upon the tube to engage said de- 130

vice, and a slidingly mounted latch having a bifurcated free end to travel above said seat.

13. The combination with an inflator, of a shiftable latch carried thereby and constructed to detachably retain the object to be inflated in connection with the inflator.

14. In a device of the class described, an inflatable balloon body, a valveless nozzle therefrom, and a depending tail disposed in 10 alinement with the discharge from said nozzle.

15. In a device of the class described, an inflatable balloon body, a valveless nozzle therefrom, a flexible connection from said 15 nozzle, and a tapering tail carried by said

connection in alinement with the discharge from said nozzle.

16. In a device of the class described, an inflatable balloon body, a valveless nozzle therefrom, a cord extending from said nozzle 20 and provided with a body at its free end, and a tail upon said body comprising separated strips of material mounted thereon.

In testimony whereof I affix my signature in presence of two witnesses.
